UNITED STATES PATENT OFFICE.

WILLIAM E. RUPLEY, OF LOS ANGELES, CALIFORNIA, ASSIGNOR TO WESTERN PIPE AND STEEL COMPANY OF CALIFORNIA, OF SAN FRANCISCO, CALIFORNIA, A CORPORATION OF CALIFORNIA.

WELDED PIPE.

Original application filed September 26, 1925, Serial No. 58,952. Divided and this application filed August 5, 1926. Serial No. 127,355.

This invention relates to welded pipe and is more particularly directed to a welded pipe formed of a continuous section of sheet metal formed to the proper curvature and secured together at a longitudinal welded end to a stove pipe casing, constructed of a plurality of concentric sections of such welded pipe, the outer of which concentric sections is welded at the longitudinal seam to the periphery of the inner section.

This application is a division of my co-pending application for welded pipe and method and apparatus for forming the same, filed September 26, 1925, Serial No. 58,952.

15 An object of this invention is to provide a welded pipe of a single sheet of steel rolled to cylindrical form and welded at a longitudinal seam and the edges of the said tubular sheets and which welded pipe is adapted to be 20 employed for a fluid conduit or which may be employed as the inner member of a stove pipe casing.

Another object of this invention is to provide a stove pipe casing made of stands of 25 casing constructed of concentric casing members, each of which concentric casing members is formed from a single portion of sheet metal rolled to the desired shape, and which concentric casings are rigidly secured one 30 to the other at a longitudinal seam.

Another object of this invention is to provide a stove pipe casing having a uniform exterior contour throughout its length so that the same will not "hang up" during the driving of the same into a well.

35 Other objects and advantages of this invention will be apparent from the following detailed description of a preferred embodiment thereof, as illustrated in the accompanying 40 drawings, in which drawings:

Figure 1 is a side elevation of a stove pipe casing embodying this invention.

Figure 2 is an end section of a welded pipe embodying this invention.

45 Figure 3 is an end sectional view taken substantially on the line 3-3 of Figure 1.

Figure 4 is a side elevation, partly in vertical section, of a fragment of stove pipe casing embodying this invention, illustrating the 50 manner of assembling the stands of casing.

In the preferred embodiment of this invention illustrated in the accompanying drawings, 1 illustrates a stand of casing which is rigidly secured to a second stand of casing 2 at

the joints or welds 3 and 4. The stands of 55 casing 1 and 2 are made up of one-piece rolled metal tubular members 5 and 6.

The inner tubular member or welded pipe 5 is formed of sheet metal rolled to the required diameter and secured together at its 60 abutting edges 5^a by means of a butt weld 7, the inner tubular member 5 being properly welded is then secured within the outer tubular member 6 which is likewise formed of a single portion of rolled sheet metal and which 65 is positioned around the inner tubular member 5 and has its abutting edges 6^a forced together and welded at a butt weld 8 to the inner tubular member 5 so that the tubular members 5 and 6 are rigidly secured together 70 at the weld 8 along the longitudinal seam which extends throughout the stand of casing.

The end 9 of the inner tubular member 5 projects from one end of the casing 6, as illustrated in Figure 4. The end 10 of the outer 75 tubular member 6 extends beyond the end of the inner tubular member 5 at the opposite end of the stand of casing, so that the end 9 of one stand of casing 1 may be fitted within the end 10 of a second stand of casing 2. The 80 projecting ends 9 and 10 are of equal length so that the end of the inner tubular member 5 abuts the ends of the second tubular member 5, and so that the upper end of the tubular outer member of the casing 2 abuts the lower 85 end of the tubular member 6 of the casing 1. Being so positioned, the abutting ends of the tubular members 6 are butt welded together and to the inner tubular member 5 in the same manner as the other tubular sections of casing 90 are illustrated as welded together in my co-pending application filed September 26, 1925 Serial No. 58,951. A plurality of perforations 11 are formed in the outer tubular member 6 of the casing 2 adjacent the upper end 95 of the inner tubular member 5 so that the abutting ends of two such tubular members 5 may be welded together and secured by the weld to the outer tubular member 6 of the stands 2 of casing.

The inner tubular members or welded pipes 5 are formed of a single portion of metal which is first rolled to approximately the desired or required diameter in any preferred or desired manner and as is well understood in 105 the art.

Having fully described a preferred embodiment of my invention, it is to be understood

that I do not wish to be limited to the exact details herein set forth, but my invention is of the scope of the appended claims.

I claim:

- 5 1. A stove pipe casing comprising an elongated inner tubular member and an elongated outer tubular member, the said inner member being concentrically positioned within the said outer member so that the end of the inner member extends beyond the end of the outer member, and a welded longitudinal seam for securing the outer member to the inner member.
- 10 2. A stove pipe casing comprising concentric inner and outer tubular members, the said outer tubular member being formed of a continuous rolled sheet of metal welded together at its abutting edges and to the said inner member.
- 15 3. A stove pipe casing comprising concentric one-piece tubular members forming a stand of casing, the outer tubular member being welded together and to the said inner tu-

bular member at a longitudinal seam.

4. A stove pipe casing comprising concentric one-piece tubular members forming a stand of casing, the outer tubular member being formed of sheet metal and secured together and to the inner tubular member at a welded longitudinal seam, and the end of the inner tubular member projecting beyond the end of the outer tubular member at one end, the end of the outer tubular member projecting beyond the inner tubular member at the opposite end of the stand.

5. A stove pipe casing comprising concentric inner and outer tubular members formed of sheets of metal, the longitudinal edges of the inner member being simultaneously welded together and to the outer member and the longitudinal edges of the outer member being simultaneously welded together and to the inner member.

Signed at Los Angeles, California, this 20th day of July 1926.

WILLIAM E. RUPLEY.
